CLAIM

The ornamental design for a high-strength partition top anchor, as shown and described.

DESCRIPTION

FIG. 1 is a front elevation view of a high-strength partition top anchor according to the first embodiment of the present invention, the rear elevation view being identical thereto; FIG. 2 is a left side elevation view of the high-strength partition top anchor of FIG. 1, the right side elevation view being identical thereto;

FIG. 3 is a top view of the high-strength partition top anchor of FIG. 1;

FIG. 4 is a bottom view thereof;

FIG. 5 is a front elevation view of a high-strength partition top anchor according to the second embodiment of the present invention, the rear elevation view being identical thereto;

FIG. 6 is a left side elevation view of the high-strength partition top anchor of FIG. 5, the right side elevation view being identical thereto;

FIG. 7 is a top view of the high-strength partition top anchor of FIG. 5; and,

FIG. 8 is a bottom view thereof.
